(57) **CLAIM**

The ornamental design for a smart swimming pool or hot tub monitor, as shown and described.

DESCRIPTION

FIG. 1 is a front and right side environmental view of the float of the present invention;

FIG. 2 is top view of the float of the present invention;

FIG. 3 is a front view of the float of the present invention;

FIG. 4 is a bottom view of the float of the present invention;

FIG. 5 is a back side view of the float of the present invention;

FIG. 6 is a right side view of the float of the present invention;

FIG. 7 is a left side view of the float of the present invention;

FIG. 8 is a front and right side environmental view of the gateway of the present invention;

FIG. 9 is top view of the gateway of the present invention;

FIG. 10 is a front view of the gateway of the present invention;

FIG. 11 is a bottom view of the gateway of the present invention;

FIG. 12 is a back side view of the gateway of the present invention;

FIG. 13 is a right side view of the gateway of the present invention; and,

FIG. 14 is a left side view of the gateway of the present invention.
